(57) **CLAIM**

The ornamental design for a safe, as shown and described.

DESCRIPTION

FIG. 1 shows a perspective view of a safe having a recharging port hole, a drop slot, a corkboard and a mirror, according to the present invention;

FIG. 2 shows a front view of the safe of FIG. 1 illustrating the safe door with the drop slot above the corkboard and the mirror on the safe door;

FIG. 3 shows a first side view of the safe of FIG. 1 illustrating the recharging port hole and door hinges;

FIG. 4 shows a second side view of the safe of FIG. 1;

FIG. 5 shows a top view of the safe of FIG. 1;

FIG. 6 shows a bottom view of the safe of FIG. 1; and,

FIG. 7 shows a back view of the safe of FIG. 1, illustrating an optional plate with holes for attaching the safe to a supporting surface.
